ABSTRACT OF THE DISCLOSURE

Production of sulfonium salts of carboxylic acids or sulfonic acids by reaction of thioethers having aliphatic, cycloaliphatic, araliphatic or aromatic radicals having up to twenty carbon atoms with alkylene oxides having two to four carbon atoms and carboxylic acids having one to twenty carbon atoms or organic sulfonic acids having an aliphatic, cycloaliphatic, araliphatic or aromatic radical having up to twenty carbon atoms, in about equivalent amounts, the reaction being carried out at temperatures of from 20° to 80° C. without using water. Sulfonium salts of carboxylic acids or sulfonic acids may be used as bactericides or textile assistants.

This invention relates to an improved process for the production of sulfonium salts of carboxylic or sulfonic acids from thioethers, alkylene oxides and carboxylic or sulfonic acids.

It is known from German printed application No. 1,224,498 that sulfonium salts of carboxylic acids are obtained when a solution of trialkylsulfonium sulfate is allowed to flow over a basic ion exchanger and the sulfonium hydroxide formed is neutralized with a carboxylic acid. This method is very expensive because it uses basic ion exchangers.

According to another method which is described in U.S. patent specification No. 3,159,682, sulfonium salts of carboxylic acids are obtained by reaction of thioethers with alkylene oxides and aqueous carboxylic acids. The process however gives yields of only 85% of the theory. The sulfonium salts prepared are very difficult to purify so that the quality in many cases does not satisfy the required standard. This is true particularly when the carboxylic acids used as starting materials are not soluble in water.

It is an object of this invention to provide an improved process for manufacturing sulfonium salts of carboxylic or sulfonic acids in a simple manner and in practically quantitative yields. Another object of this invention is to provide an improved process by which sulfonium salts of carboxylic acids or sulfonic acids are immediately obtained in great purity.

In accordance with this invention, these and other objects and advantages are obtained in an improved process for the production of sulfonium salts of carboxylic or sulfonic acids by the reaction of thioethers which have aliphatic, cycloaliphatic, araliphatic or aromatic radicals having up to twenty carbon atoms, with alkylene oxides having two to four carbon atoms and carboxylic acids having one to twenty carbon atoms or organic sulfonic acids which have aliphatic, cycloaliphatic, araliphatic or aromatic radicals having up to twenty carbon atoms, in about equivalent amounts, the improvement consisting in carrying out the reaction at temperatures of 20° to 80° C. without using water.

We have now found that sulfonium salts of carboxylic or sulfonic acids are advantageously obtained by reaction of thioethers with alkylene oxides and carboxylic or sul-

2

fonic acids by carrying out the reaction at 20° to 80° C. without using water.

The new process has the advantage that sulfonium salts of carboxylic or sulfonic acids are immediately obtained in great purity in a simple way in practically quantitative yields.

The new process is remarkable because it is stated in U.S. patent specification 3,159,682 that the process proceeds with adequate yields only in the presence of water, preferably at temperatures of from 0° to 20° C. Furthermore it is necessary to overcome a prejudice to carry out the reaction at temperatures of more than 50° C. because in British patent specification No. 1,058,075 it is stated that hydroxyalkylcarboxylic esters are formed in the reaction of carboxylic acids with epoxides in the presence of sulfonium salts and/or thioethers.

It is preferred to use for the reaction carboxylic acids having 1 to 20 carbon atoms such as acetic acid, propionic acid, caproic acid, lauric acid, stearic acid, oleic acid, adipic acid, palmitic acid, polyacrylic acid, citric acid, maleic acid, oxalic acid, phthalic acid, terephthalic acid and trifluoroacetic acid.

Preferred sulfonic acids are organic sulfonic acids which have an aliphatic, cycloaliphatic, araliphatic or aromatic radical having up to twenty, particularly up to eighteen, carbon atoms. They may contain the sulfonic acid group one or more times, for example one to four times, in the molecule. Moreover they may be unsaturated, for example may contain one or two olefinic double bonds or substituents which are inert under the reaction conditions, such as halogen atoms or alkoxy groups having one to four carbon atoms. It is however also possible to use for the reaction, compounds which contain more than four sulfonic acid groups in the molecule, for example polyvinylsulfonic acid. Monosulfonic acids containing an alkyl radical, aralkyl radical or aryl radical having up to eighteen carbon atoms are preferred particularly. Examples of suitable sulfonic acids are: methylsulfonic acid, butylsulfonic acid, octylsulfonic acid, dodecylsulfonic acid, tridecylsulfonic acid, cyclohexylsulfonic acid, cyclooctylsulfonic acid, benzylsulfonic acid, dodecylbenzenesulfonic acid, benzenesulfonic acid, naphthalene-2-sulfonic acid, naphthalene-1-sulfonic acid, benzene-1,3-disulfonic acid, naphthalene-1,5-disulfonic acid or polyvinylsulfonic acid.

Long chain aliphatic or araliphatic sulfonic acids having twelve to eighteen carbon atoms, which contain one sulfonic acid group in the molecule and which, apart from the sulfonic acid groups have hydrocarbon structure have special importance.

Thioether, alkylene oxide and carboxylic acid or sulfonic acid are advantageously reacted in equivalent amounts. Slight deviations from the equivalent amounts are possible. When using dicarboxylic acids, polycarboxylic acids or polysulfonic acids it is possible to react only part of the carboxyl or sulfonic acid groups.

The reaction proceeds at temperatures of from 20° to 80° C. Particularly good results are achieved at temperatures of 30° to 60° C. When starting materials which are gaseous at room temperature are used in the liquid phase, or temperatures are used which are above the boiling point of the starting materials, the reaction may be carried out at superatmospheric pressure, for example at up to 30 atmospheres.

It is an essential feature of the invention that the reaction is carried out without using water; this does not mean that absolutely no water may be present in the reaction mixture. Small amounts of water, for example 1 to 2% by weight, which are often contained in the starting materials do not affect the reaction.

The process according to the invention may be carried out for example by placing thioether and carboxylic

or sulfonic acid in a stirred vessel and adding the specified amount of an alkylene oxide at the specified temperature. When gaseous ethylene oxide is used as the starting material, it may be passed in as a gas at atmospheric pressure or it may be metered in under pressure as a liquid. The reaction is in general over after three to forty-eight hours. The melt obtained need not be further purified, because the reaction proceeds almost quantitatively.

Sulfonium salts of carboxylic acids or of sulfonic acids which are prepared by the process according to this invention are suitable as bactericides and as textile assistants (cf. U.S. patent specification No. 3,159,682).

The invention is illustrated by the following examples in which the parts mentioned are parts by weight.

EXAMPLE 1

A mixture of 200 parts of lauric acid and 125 parts of technical grade thiodiglycol (98%) is heated to 44° C. in a stirred vessel. Then 50 parts of ethylene oxide is passed in during the course of fifteen hours at 40° C. and the whole is allowed to cool. 370 parts of tris-(β -hydroxyethyl)-sulfonium laurate is obtained having a melting point of 101° to 105° C.

Analysis.—Calc'd for (percent): C, 59.3; H, 10.38; O, 21.84; S, 8.74. Found (percent): C, 59.3; H, 10.5; O, 21.7; S, 8.3.

EXAMPLE 2

25 parts of ethylene oxide is passed in the course of fifteen hours at 60° C. into a melt of 128 parts of palmitic acid and 62.5 parts of technical grade thiodiglycol (98%) in the manner described in Example 1. After the melt has cooled, 213 parts of tris-(β -hydroxyethyl)-sulfonium palmitate is obtained which has good solubility in water and a melting point of 94° to 96° C. The yield is 100% of the theory.

EXAMPLE 3

In a manner analogous to that in Example 1, 282 parts of oleic acid, 125 parts of technical grade thiodiglycol (98%) and 50 parts of ethylene oxide are reacted at 30° C. 426 parts of tris-(β -hydroxyethyl)-sulfonium oleate is obtained. The yield is 100% of the theory.

EXAMPLE 4

In a manner analogous to that described in Example 1, 286 parts of stearic acid and 125 parts of technical grade thiodiglycol (98%) are reacted with 50 parts of ethylene oxide at 60° C. in the course of fifteen hours. 430 parts of tris-(β -hydroxyethyl)-sulfonium stearate is obtained having a melting point of 85° C. The yield is 100% of the theory.

EXAMPLE 5

83 parts of terephthalic acid and 125 parts of technical grade thiodiglycol (98%) are reacted with 50 parts of ethylene oxide at 30° to 40° C. as described in Example 1. The reaction is over after forty-eight hours. 249 parts of (tris-(β -hydroxyethyl)-sulfonium terephthalate is obtained as a colorless melt which crystallizes after some time. After recrystallization from alcohol, colorless crystals having a melting point of 107° to 110° C. are obtained. The yield is 100% of the theory.

EXAMPLE 6

58 parts of maleic acid and 125 parts of technical grade thiodiglycol (98%) are reacted with 50 parts of ethylene oxide in a manner analogous to that described in Example 1. The reaction is over after five to six hours. 230 parts of bis-(tris-(β -hydroxyethyl)-sulfonium) maleate is obtained as a colorless viscous melt having the refractive index $n_{D}^{20}=1.5208$.

EXAMPLE 7

60 parts of acetic acid and 125 parts of technical grade thiodiglycol (98%) are reacted with 50 parts of ethylene

oxide in a manner analogous to that in Example 1. A colorless viscous liquid is obtained having the refractive index $n_{D}^{20}=1.5052$ which crystallizes upon prolonged standing. The tris-(β -hydroxyethyl)-sulfonium acetate is strongly hygroscopic and melts at 102° to 104° C. The yield is 100% of the theory.

EXAMPLE 8

A mixture of 128 parts of palmitic acid and 62 parts of thiodiglycol is heated at 65° C. in a stirred vessel. 46 parts of epichlorohydrin is added in the course of two hours. 236 parts of bis-(β -hydroxyethyl)-2-hydroxy-3-chloropropylsulfonium palmitate of a waxy consistency is obtained which melts at 91° C. after it has been recrystallized from acetone.

EXAMPLE 9

100 parts of lauric acid is reacted in a stirred vessel with 61 parts of thiodiglycol and 46 parts of epichlorohydrin at 42° C. 207 parts of bis-(β -hydroxyethyl)-2-hydroxy-3-chloropropylsulfonium laurate is obtained having a melting point of 57° to 58° C.

EXAMPLE 10

568 parts of stearic acid and 244 parts of thiodiglycol are heated to 70° to 80° C. in a reactor and then reacted with 184 parts of epichlorohydrin. 996 parts of bis-(β -hydroxyethyl)-2-hydroxy-3-chloropropylsulfonium stearate having a melting point of 62° to 63° C. is obtained.

EXAMPLE 11

142 parts of oleic acid and 61 parts of thiodiglycol are heated to 40° to 50° C. in a stirred vessel and then reacted with 46 parts of epichlorohydrin. After reaction has continued for another three hours 50° C., 249 parts of bis-(β -hydroxyethyl)-2-hydroxy-3-chloropropylsulfonium oleate is obtained as a viscous yellow oil.

EXAMPLE 12

132 parts of benzoic acid and 122 parts of thiodiglycol are placed in a reactor. The mixture is heated to 60° C. and then reacted with 92.5 parts of epichlorohydrin. 346 parts of bis-(β -hydroxyethyl)-2-hydroxy-3-chloropropylsulfonium benzoate is obtained as a viscous liquid.

EXAMPLE 13

187 parts of thiodiglycol is placed in a stirred vessel and 380 parts of 86% by weight dodecylbenzenesulfonic acid is introduced and 60 parts of ethylene oxide is passed in as a gas at the same time in the course of two to three hours at 20° to 40° C. The reaction is allowed to continue for another three hours at room temperature. 627 parts of a highly viscous syrup is obtained which dissolves in water to give a clear neutral solution. The syrup obtained has a refractive index

$$n_{D}^{20}=1.5172$$

and the content of tris-(β -hydroxyethyl)-sulfonium dodecylbenzenesulfonate is about 85% by weight. This content is determined by ascertaining the sulfur content after the sulfate ions have been removed with barium hydroxide.

EXAMPLE 14

125 parts of 98% thiodiglycol is placed in a stirred vessel and at 20° to 40° C. in the course of two hours 172 parts of p-toluenesulfonic acid is introduced and 46 parts of ethylene oxide gas passed in simultaneously. The reaction is then allowed to continue for another twelve hours at 30° to 40° C. 343 parts (about 99% of the theory) of tris-(β -hydroxyethyl)-sulfonium p-toluenesulfonate is obtained as a viscous syrup which dissolves in water to give a clear solution and has a refractive index $n_{D}^{20}=1.5375$.

I claim:

1. An improved process for the production of sulfonium salts of carboxylic acids or sulfonic acids by reaction

of thioethers which have aliphatic, cycloaliphatic, araliphatic or aromatic radicals having up to twenty carbon atoms with alkylene oxides having two to four carbon atoms and carboxylic acids having one to twenty carbon atoms or organic sulfonic acids which have an aliphatic, cycloaliphatic, araliphatic or aromatic radical having up to twenty carbon atoms in about equivalent amounts, wherein the improvement consists in carrying out the reaction at temperatures of from 20 to 80° C. in the presence in the reaction mixture of not more than 2% by weight of water.

2. A process as claimed in claim 1 in which a thioether is used which has an alkyl radical having one to twenty carbon atoms.

3. A process as claimed in claim 1 in which bis-(β -hydroxyethyl)thioether is used.

4. A process as claimed in claim 1 in which bis-(β -hydroxypropyl)thioether is used.

5. A process as claimed in claim 1 in which ethylene oxide is used as the alkylene oxide.

6. A process as claimed in claim 1 in which propylene oxide is used as the alkylene oxide.

7. A process as claimed in claim 1 in which an aliphatic monocarboxylic acid is used which has one to eighteen carbon atoms.

8. A process as claimed in claim 1 in which an aliphatic sulfonic acid having twelve to eighteen carbon atoms is used.

9. A process as claimed in claim 1 in which an araliphatic sulfonic acid having twelve to eighteen carbon atoms is used.

10. A process as claimed in claim 1 carried out at a temperature of from 30° to 60° C.

11. A process as claimed in claim 1 carried out at superatmospheric pressure up to 30 atmospheres.
